UNITED STATES PATENT OFFICE.

WILLIAM FREEMON SPURLING, OF ISLINGTON, LONDON, ENGLAND.

HOOD FOR ROAD-VEHICLES.

1,118,246.

Specification of Letters Patent.

Patented Nov. 24, 1914.

Application filed August 18, 1913. Serial No. 785,200.

To all whom it may concern:

Be it known that I, WILLIAM FREEMON SPURLING, of 19 Mantell street, Islington, in the county of London, England, have invented certain new and useful Improvements in Hoods for Road-Vehicles, of which the following is a specification.

This invention relates to road vehicle hoods of the kind wherein a rear hood frame, comprising two or more upwardly extending diverging hoop members, is connected by two substantially parallel links to a forwardly extending structure which supports the front part of the hood.

15 The objects and advantages of the invention, as well as the novel features thereof, will be hereinafter more particularly described and then specifically pointed out in the appended claims.

20 Referring to the drawings which show some forms of the invention:—Figure 1 is a side view of a hood attached to a motor-car; Fig. 2 shows a modification of the invention; Fig. 3 shows a further modification.

25 In Fig. 1 the complete framework comprises five hoop members *a*, *b*, *c*, *d*, and *e*, extending across and supporting the hood. The hoops *a* and *c* are pivotally connected to the car body and when erected form a V. The hoop *b* is pivoted to the hoop *a* about half way up the side of the hoop. The hoop *a* is rearwardly inclined and the hoops *b* and *c* forwardly inclined so that the two hoops *b* and *c* are approximately parallel to one another. From the hoop *b* a link or rod *h* of the hood extends which is pivoted to the hoop *b*. This link or rod *h* is the rearward link of the overhanging hood extension and one of the end links referred to in the claims. The link or rod *h* is pivotally connected to the lower end of the hoop *d* at a point about coincident with the lower edge of the overhead extension.

45 The hoop *d* is forwardly inclined and has a link *m* also formed an end link of the forward extension pivoted to it at *n*, one end of said link being pivotally connected to the hoop *c* at *o*, and the other end being pivotally connected to the end of the hoop *e* at *p*. The hoop *e* lies substantially horizontal when the hood is open and approximately coincident with the lower edge of the overhead extension. A link *q*, pivotally connected to the hoop *d* and hoop *e* is arranged to support the hoop *e* from the

hoop *d*. A supplementary suspending link *t* is employed which is pivoted at *o* to the hoop *c* and to the rod *h* at *u*.

The invention has been described as relating to one side of the hood only, for the sake of convenience, but it will be understood that the other side of the hood is identical.

When the hood is to be folded the hoop *e* can be pushed backward, when the lazy tongs levers will close together and collapse together with the main portion of the hood.

The rod *h* may be provided with suitable means such as a spring or spring catch or other frictional retaining device, to engage with the hoop *c* to steady the parts against lateral movement.

It is to be understood that a more or less number of hoops may be employed with the sliding rod connection, the arrangement of the pivots being suitably modified for the purpose. For example Fig. 2 shows diagrammatically a hood similar to Fig. 1 with a shorter extension in front.

Fig. 3 shows a construction somewhat similar to Fig. 2 which is adapted for what is known as a "two seater car." In this construction the forward extension of the hood consists of the rod *m* and the hoop *e* the latter being now connected to the end of the rod *h*, the link *t* is arranged as before but the rear part of the rod *h* is preferably curved as shown.

What I claim and desire to secure by Letters Patent is:—

1. In a hood for vehicles, an upright hoop, an upwardly and rearwardly inclined hoop, a substantially horizontal front hoop, a suspending link pivotally connected to the horizontal and upright hoops, a horizontal link pivotally connected at its rear end to the inclined rear hoop, a second suspending link pivotally connected at one end to the first-mentioned suspending link and to the upright hoop and at its other end to the horizontal link, and means connecting the forward end of the horizontal link with the horizontal hoop.

2. In a hood for vehicles, an upright hoop, an upwardly and rearwardly inclined hoop pivotally connected therewith, a substantially horizontal front hoop, a suspending link pivotally connected to the horizontal and upright hoops, a horizontal link pivotally connected at its rear end to the inclined rear hoop, a second suspending link pivot-

ally connected at one end to the first-mentioned suspending link and to the upright hoop at a point above the plane of the horizontal link and at its other end to the horizontal link between the ends of the latter, and means connecting the forward end of the horizontal link with the horizontal hoop.

In testimony whereof I have signed my name to this specification in the presence of two subscribing witnesses.

WILLIAM FREEMON SPURLING.
